STRING ANCHORING FITMENT FOR
TENNIS RACKETS

Charles L. Godfrey, Jackson Heights, N. Y.

Application January 15, 1947, Serial No. 722,205

3 Claims. (Cl. 273—73)

1

This invention relates to tennis rackets, and, more particularly, has reference to the manner of mounting the strings of the racket where the latter are threaded through apertures in the racket frame, for facilitating fabrication of the racket, and for reducing the manufacturing expense even though an extra fitment is employed in connection with some or all of the strings, while, above all, providing a racket which will have an improved action in use.

As is well known a tennis racket includes a suitable frame provided with crossed strings providing a striking surface relative to the tennis ball to put the same in flight or to intercept the same while in flight. The crossed strings are usually of resilient catgut which should be placed and maintained under high tension.

In the making of tennis rackets, a problem is to provide a frame which may yield to some extent, yet a frame which is stiff and sturdy enough to take stresses transmitted to it from the strings while the game is being played. If the frame is rigid and the strings drawn too tight, they may break, while if the frame is flexible to any appreciable extent, it does not have the requisite strength. In other words, a problem has long been to provide some practicable form of elastic or resilient means between the catgut or the like and the frame where the former engages the latter, rather than to deprive the frame of any of its ideal degree of rigidity and resistance to flexure.

An object of the invention is to provide an improved tennis racket which shall have the advantage of incorporating a playing surface of high resiliency without subjecting the frame or strings of the racket to the danger of injury.

Another object is to provide an improved resilient means for interposition between meeting frame and string parts; and by an improved such means is meant a practicable one, from the standpoint of cost and manufacture and ease of ready incorporation in making a tennis racket, as well as improved action in use.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevation in miniature of a tennis racket constructed according to a now preferred embodiment of the present invention.

2

Fig. 2 is a fragmentary showing of a part of the racket frame such as that at a location indicated by the bracket 2 of Fig. 1; said frame part being shown partially in elevation and partially in section so as to illustrate a utility of the invention where, for instance, a plurality of string stretches pass through merely one of the apertures extending through the frame; the parts here being drawn to about twice the actual scale.

Fig. 3 shows, partially in side elevation and partially in axial section, and on a scale about eight times the actual size, one of the fitments shown in Fig. 2 as inserted in each of various 15 of said apertures, and so that, as shown in Fig. 2, one or more string stretches may pass through the hollow interior of a single fitment.

Fig. 4 is a top plan view of the fitment of Fig. 3; the enlarged head of said fitment providing, 20 in combination with the like heads of a plurality of the fitments adjacently used on the frame, the improved resilient means of the present invention.

Referring now to the drawings more in detail, 25 there is shown at 5 a tennis racket strung, for example, in the manner shown in my earlier U. S. Patent Number 1,773,960. Rigid on a handle 6 is a frame 7 and the latter is strung with catgut or the like to provide a playing surface within the confines of the frame. As is well understood in the art of making tennis rackets, the playing surface is a mesh or network of criss-crossed string stretches, each stretch running from one point on the frame to another. Ordinarily, a plurality of parallel 30 stretches are crossed by another plurality of parallel stretches, with the latter having directions of extension at right angles to that of the first mentioned plurality. The criss-crossing 35 strings are generally interwoven.

According to the more usual or simpler way of providing the playing surface, merely one string length is used, which, in passing through all but the first and the last transverse apertures of the frame is given a U-bend, at the junction of a stretch sent through an aperture from the inner end thereof with the next following stretch sent through the next aperture of the frame from an outer point thereof, so that what may be called the bowl of the U lies flatwise against the outer side of the frame.

In certain rackets, however, as in the one of the patent aforesaid, as shown in Fig. 1 hereof, the central part of the playing surface is given a double complement of stretches, or rather, at

the central part of the playing surface the extra stretches are arranged relative to the others in such manner that a smaller mesh and hence more sharply resilient area of the playing surface is provided at the center thereof. In such case, as will be understood, two strings are employed, and portions of both strings pass through each of certain of the frame apertures. The apertures just referred to are ordinarily the ones the locations of which are indicated in Fig. 1 by small protuberances at the outer periphery of the frame and arranged in four groups of six each, these groups marked 8, 9, 10 and 11.

Each of said protuberances is roughly indicative of the enlarged upper end 12 of a fitment 14 of the kind illustrated on a very large scale in Figs. 3 and 4, and on a scale of about twice actual size in Fig. 2.

In the case where any string stretch is singly passed through an aperture in the frame, fitments 14 may be used in all such apertures; but this arrangement is not shown in Fig. 1, in order to permit the groups of apertures 8 through 11 above mentioned to be there readily located.

The apertures through the part of the frame 7 illustrated in Fig. 2, of which apertures the one there shown in section is marked 16, may be taken as representing apertures in the group 8 of Fig. 1. The two string stretches shown as passing through the apertures of Fig. 2 are there marked 17 and 18, respectively.

It will be noted that a central bore 19 through the fitment 14 is illustrated in Fig. 2, as large enough to permit passage through the fitment of two string stretches.

With the fitment employed at a location around the frame such that only one string stretch there terminates, the diameter of said bore and consequently the diameter of the stem or shank portion 20 of the fitment may be correspondingly reduced.

However, with the fitments 14 molded, as is preferred, to render their cost negligible once the cost of the molding dies have been amortized, it is recommended that all the fitments, wherever used on the frame, be alike, that is, have a bore large enough in diameter to accommodate two adjoining portions of two different strings wherever desired. Thereby merely the expense of making only one molding die will be involved. In view of the plastic material satisfactorily used, Vinylite, the fitment all over may have a wall thickness of somewhat less than $\frac{1}{32}$ ".

Then the stem or shank 20 of the fitment 14 may be slipped from the outer side of the frame into any aperture thereof, yet with such aperture only negligibly of greater diameter than that of said aperture as heretofore drilled through the frame for directly taking a single string or a pair of strings. Where, as in Fig. 1, some apertures are to be traversed by one string, and others by a plurality of strings, the practice is to drill all the apertures to the same diameter. Hence, present practice and economies can be retained.

Also, a saving is effected fully equal to the cost of the fitments, because when they are used, the previous conical countersinkings (not shown) at the outer ends of the apertures may be omitted. These last noted formations, having to be established one after another relative to all the apertures, are to eliminate sharp corners across which a string inserted into an aperture from the outer end of the latter must be drawn

very tight to assist in establishing the playing surface of the racket.

As will be noted from the drawings, a pair of longitudinally convex diametrically aligned grooves 22 are provided across the top of an arched substantially dome-shaped head 12 of the fitment; thus eliminating any necessity to countersink the apertures at their outer ends.

The resilient means provided by the present invention results from the behavior of such a resilient plastic as Vinylite, when a fitment 14 molded therefrom is shaped as shown, that is, to have its head 12 generally dome-shaped, and when, at suitable points around the head, for example as here illustrated, the head is given attenuated triangular cut-outs 23.

As will be seen from a comparison of Figs. 3 and 4, the inner ends of these cut-outs almost reach the upper end of the stem or shank 20.

When the string or strings used to establish the playing surface are finally drawn to normal degree of tightness, and then knotted in place, a playing surface of accepted general action is obtained. Often however, and at times not to be anticipated, as in serving or returning the ball, there is an extra heavy impact against the playing surface. At that instant, there should be some yield, but a perfectly resilient one, so that as soon as the unusually heavy shock received by the playing surface and transmitted to the frame is absorbed before damage can be done, the playing surface is instantaneously restored to its normal condition.

The four segments of the head 12 of a fitment 14 are compressed to some extent, when the string or strings are finally tightened and knotted at the racket factory. The result is that the resilient action of the thus compressed two sectors across which the groove formations 22 extend is exceedingly stiff yet highly resilient.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In combination with a tennis racket frame having an opening for the passage of a string, a fitment comprising a tubular shank inserted into the opening, a dome-shaped head having arched projections separated by cutouts formed on the outer end of said tubular shank and bearing against the outer face of said racket, whereby said string may be passed through said shank and across said dome-shaped head providing a resilient end anchor for the string.

2. In combination with a tennis racket frame having an opening for the passage of a string, a fitment comprising a tubular shank inserted into the opening, a dome-shaped head having arched projections separated by cutouts formed on the outer end of said tubular shank and bearing against the outer face of said racket, whereby said string may be passed through said shank and across said dome-shaped head providing a resilient end anchor for the string, said dome-shaped head being formed with laterally extending diametrically opposite grooves for receiving and guiding said string after passing through said tubular shank, said cutouts being extended inwards from the periphery of said head and ar-

ranged in pairs on opposite sides of said grooves.

3. In combination with a tennis racket frame having an opening for the passage of a string, a fitment comprising a tubular shank inserted into the opening, a dome-shaped head having arched projections separated by cutouts formed on the outer end of said tubular shank and bearing against the outer face of said racket, whereby said string may be passed through said shank and across said dome-shaped head providing a 10 resilient end anchor for the string, said cutouts being extended radially inwards from the periphery of said head.

CHARLES L. GODFREY.
